UNITED STATES PATENT OFFICE.

ALBERT M. CORTEZ, OF SAN FRANCISCO, CALIFORNIA.

SHIP.

Specification of Letters Patent.

Patented July 8, 1919.

1,309,019.

Application filed December 19, 1918. Serial No. 267,498.

To all whom it may concern:

Be it known that I, ALBERT M. CORTEZ, a citizen of the Republic of Portugal, residing in the city and county of San Francisco, 5 State of California; have invented certain new and useful Improvements in Ships, of which the following is a full, clear, and exact description, such as will enable others skilled in the art to which it appertains to 10 make and use the same.

My invention relates to improvements in ships wherein an improved construction operates to produce a new arrangement of compartments to facilitate the prevention 15 of the destruction of the ship, and to facilitate the movement of the ship after the hull has been penetrated.

The primary object of the present invention is to provide a new and improved construction for a non-sinkable ship.

Another object of the improvement is to provide an improved arrangement of bulkheads extending rearwardly from a central bulkhead to the sides of the ship in such a 25 manner that a series of closely spaced bulkheads will be provided adjacent the sides of the ship so that torpedoes and the like will be deflected or resisted by a series of walls or bulkheads to prevent the resulting explosions from extending into the ship to any 30 great extent.

I accomplish these objects by means of the improved construction disclosed in the drawings and set forth in the claims.

35 Figure 1 is a plan view of a ship, one portion of said view being in section taken on line 1—1 of Fig. 2 in the direction indicated by the arrows; and

Fig. 2 is a broken side elevation of a ship 40 partly in section as taken on the irregular line 2—2 of Fig. 1.

Referring to the drawings, the hull A is provided with a central well B within which are located the motors C and boilers D.

45 The hull A is provided with several decks E, and a central vertically disposed bulkhead G extends from the well B in both directions to divide the hull A and the compartments between the decks E longitudinally.

Within each compartment between the decks E I have provided a series of vertically disposed arcuate bulkheads J which extend from both sides of the bulkhead G 55 and rearwardly to the sides of the ship A.

The upper portion of each bulkhead J is

inclined and curved toward the bow of the ship A, as shown in Fig. 2 of the drawings.

Similar arcuate bulkheads M are arranged between the side walls of the well B and the 60 sides of the ship A.

Suitable hatches L are provided to render the compartments between the bulkheads J and the decks E readily accessible for the storage of freight. Suitable watertight 65 doors may be provided between the arcuate compartments provided between the arcuate bulkheads J.

Preferably, the decks E do not extend to the extreme forward portion of bow of the 70 hull A. In my preferred construction I provide two vertically disposed arcuate bulkheads H which extend from top to bottom of the hull A in a more closely spaced relation than the vertically disposed bulkheads J 75 whereby two comparatively narrow compartments may be provided. The outermost compartment between the outermost bulkhead H and the extreme forward portion or bow of the hull A is packed with closely 80 packed cork or a similar resilient material. This is provided to present a resistance to torpedoes or floating mines which the ship may encounter in a forward movement thereby tending to lessen the force or shock 85 on the remaining portion of the hull A.

From the foregoing it is obvious that a series of rearwardly extending compartments will be formed between decks, which compartments taper toward the sides of the 90 ship A thereby providing a series of narrow spaces separated by closely spaced outer ends of the bulkheads J. This arrangement presents a series of walls or bulkheads in closely 95 spaced relation through which a torpedo or the like must pass before reaching the interior or central portion of the hull.

As the bulkheads J are arranged substantially parallel to the bow of the ship or hull A it is evident that, operating on the injector 100 principle, surrounding water passing rearwardly of the ship while said ship is in forward or normal movement will be deflected instead of being "scooped" into a perforated compartment.

105 Should an entire compartment be blown away by the explosion of a torpedo or the like the next adjacent or present wall or bulkhead J being of substantially the same shape and inclination of the bow, will tend to facilitate instead of retard the forward movement of the ship instead of presenting

a lateral obstruction in the shape of a transverse bulkhead as employed in the present state of the art.

In this case the inclined and curved upper portion K of the presented bulkhead J will also tend to facilitate the "riding" of the ship over heaving seas, and the like by deflecting encountered waves downwardly.

It is obvious from the foregoing that I have provided an improved construction for ships and the like having a series of rearwardly extending bulkheads forming rearwardly extending compartments, said bulkheads forming closely spaced resistance means at the sides of the ship.

I claim:—

1. A ship comprising a hull; a central bulkhead dividing the hull longitudinally; and arcuate vertically disposed bulkheads extending from the central bulkhead to the sides of the ship and arranged at an angle to said central bulkhead and sides, the upper parts of the vertically disposed bulkheads being inclined toward the bow of the ship.

2. A ship comprising a hull; a central bulkhead dividing the hull longitudinally; and arcuate vertically disposed bulkheads extending at an angle from the central bulkhead and rearwardly to the sides of the hull, the upper parts of the vertically disposed bulkheads being inclined toward the bow of the ship.

3. A ship comprising a hull; a central bulkhead dividing the hull longitudinally; and arcuate vertically disposed bulkheads extending at an angle from both sides of

the central bulkhead and rearwardly to the sides of the ship; the upper portions of said vertically disposed bulkheads being curved toward the bow of the ship.

4. A ship comprising a hull having a central well for engines and boilers and several decks within said hull; a central bulkhead dividing the spaces between the decks longitudinally beyond each end of the central well; a series of arcuate vertically disposed bulkheads arranged between the decks and extending at angles from both sides of the central bulkhead and rearwardly to the sides of the ship, the upper portions of said vertically disposed bulkheads being curved toward the bow of the ship.

5. A ship comprising a hull; a vertically disposed central bulkhead dividing the hull longitudinally, two arcuate bulkheads arranged adjacent the bow of the ship and extending from said bow rearwardly to the sides of the hull to provide two compartments; a filling of cork within the space between the outer bulkhead and the bow of the ship; several decks within the hull; and a series of arcuate vertically disposed bulkheads extending from both sides of the central bulkhead rearwardly to the sides of the ship, the upper portions of said bulkheads being curved toward the bow of the ship.

In witness whereof I hereunto set my signature in the presence of two subscribing witnesses.

ALBERT M. CORTEZ.
